UNITED STATES PATENT OFFICE.

HENRY C. SWAN, OF OSHKOSH, WISCONSIN.

VEHICLE-GEAR.

SPECIFICATION forming part of Letters Patent No. 388,380, dated August 21, 1888.

Application filed April 11, 1888. Serial No. 270,289. (No model.)

To all whom it may concern:

Be it known that I, HENRY C. SWAN, of Oshkosh, in the county of Winnebago and State of Wisconsin, have invented certain new and useful Improvements in Vehicle-Gears; and I do hereby declare the following to be a full, clear, and exact description of the invention, such as will enable others skilled in the art to which it appertains to make and use the same.

10 My invention relates to an improvement in vehicle-gears, and more particularly to a type in which fifth-wheels or circle-plates are employed.

One object of my present invention is to so 15 construct vehicle-gears that the use of a loose king-bolt may be dispensed with and strength as well as lightness secured.

A further object is to furnish a light, strong, compact, and shapely device which, when attached to the front axle and forward part of the vehicle, will afford a means for the swinging movement of the front axle and wheels, and also provide for an adjustment of worn parts to take up lost motion and thus prevent rattling of the same.

With these objects in view my invention consists in certain features of construction and combinations of parts that will be hereinafter described, and pointed out in the claims.

30 Referring to the drawings, making a part of this specification, Figure 1 is a front elevation of the vehicle-gears. Fig. 2 is a side elevation, in section, of the front portion of the running-gears of a vehicle, taken on the line $x-x$, Fig. 35 1. Fig. 3 shows a bottom plan view of the top plate of the fifth-wheel and attached parts. Fig. 4 is a top plan view of the bottom plate of the fifth-wheel. Fig. 5 is a detached top view of a clamping-plate that is located on the bottom surface of the axle, it being clipped to the axle and its wooden stock. Figs. 6 and 40 7 are top and side views of a bracket-guard plate which serves to hold the two circle-plates of the fifth-wheel together and affords a means 45 for taking up lost motion in the wearing pivot-center.

D represents the central portion of a metallic vehicle-axle, of the usual form, on which the wooden cap-piece C is fitted to give form 50 and finish to the axle proper. On a flattened center portion of the cap C the fifth-wheel is

mounted, which consists of two circle or ring plates, G H, that are shown in Figs. 3 and 4.

The lower circle-plate, H, is provided with an integral cross-bar, B, which is depressed its 55 thickness below the lower surface of the circle-plate. On an edge of the cross-bar B an ear, p, is formed, from which projects an integral cylindrical pin, P, as shown in Fig. 2. The upper circle-plate, G, is made of equal diameter with the lower plate, H, and it is likewise provided with an integral transverse plate, A, that offsets from the top surface of the same. One edge of the plate A lies near the diametrical center of the circle-plate G, and an integral reach-plate, A', is extended from this edge 60 rearwardly.

At the center of the circle-plate G a depending boss is formed on the reach-plate A', which boss is perforated at R (see Fig. 3) for the reception of the true cylindrical pin P, that in effect becomes a king-bolt, on which the front 65 axle and wheels may be laterally moved as a center of vibratory motion.

Upon the transverse plate A of the upper 70 circle, G, a head-block, E, is mounted and secured by clip-plates e^2 and bolts e' , which latter extend vertically through the ears e that are formed on the parallel edges of the plate A and also through holes in the ends of the clip- 75 plates that are placed upon the lower half, F, of an elliptic plate spring, which is mounted upon the head-block E in the usual manner.

The head-block E is mortised near its center of length to receive a tenon, b, formed on the 80 front end of the wooden reach S, beneath which the plate A' is extended and secured by a screw-bolt, T', which penetrates vertically 85 through the reach and plate.

Below the fifth-wheel plates G H a bracket- 90 plate, I, is secured by the bolt T', which is inserted through the reach and its plate, as just stated, the nut of said bolt bearing against the lower surface of the bracket-plate, so as to bind the reach S, reach-plate A', and bracket- 95 plate I together, as shown in Fig. 2.

On the rear end of the bracket-plate I an offset bend is formed, which produces a shoulder, o', that engages the inner surface of the adjacent circle-plates G H loosely, the downward and rearward integral projection of the bracket-plate at this point forming a lug o,

which is adapted to support the two fifth-wheel plates and allow the lower plate, H, to slide upon the top plate, G.

The bracket-plate I is further provided with a depending and forwardly-extended portion, I', which projects its end I² below the integral pin P, as shown in Fig. 2, this part I² being perforated and screw-tapped to receive a threaded set-bolt, k, on which a jam-nut, L, is placed to secure the adjustment of the set-bolt at any desired point, this bolt being made to bear on the ear p, so as to properly elevate the lower circle-plate, H, and thus take up lost motion between the two circle-plates and also between the pin P and its receiving-socket hole R.

It should be here explained that the reach-plate A' and the bracket-plate I are provided with the mating ears w w x x, formed on their edges, said ears being perforated for the reception of the proper screw-bolts that are adapted to hold these parts together firmly, so that the functions of the bracket-plate I, as previously explained, may be properly carried into effect.

Below the central portion of the axle D a clamping-plate, N, is located, which serves as a keeper to receive the clip-bolts c c, (see Fig. 1,) that embrace the wooden cap-piece C and axle D, their threaded lower ends, c', entering the perforated ears s s, formed on the side edges of the clamping-plate near each end, as shown in Fig. 5, the clip-bolts having suitable nuts placed on their lower ends, which bear against the clamping plate to secure the cap-piece C, axle D, and plate N together, as shown in Fig. 1. The clamping-plate N is further provided with a lateral projection, V, which is formed on its rear edge near the center of length of said plate. This projection is rounded on its edge, and has a depending pin, O, formed on its lower side—that is, in vertical alignment with the upper cylindrical pin, P.

Upon the pin O a stay-brace, M, is swivel-connected by engagement of its perforated flattened end M' therewith, this end of the brace being held in place by a nut or other suitable means. The stay-brace M is rearwardly and upwardly projected, of a length to permit its other end, r, to be secured against the lower surface of the reach-plate A' by a bolt, t, which is inserted downwardly through perforations made in the reach S, reach-plate A', and pad end of the diagonal stay-brace M, these parts being clamped together firmly by the bolt and its nut, as shown in Fig. 2.

It is apparent from the manner of construction of the vehicle-gears herein described that the pins P and O will coact together and permit a free swinging motion of the front axle and the lower circle-plate, H, upon the top plate G, thus effecting a proper movement of

the front portion of the gears without requiring a perforation of the reach S, that would weaken it.

The provision of the bracket-plate I serves to hold the lower circle-plate, H, in proper relative position with regard to the upper circle-plate, G, and affords a simple and reliable means in its set-bolt K and jam-nut L to adjust these parts together, so as to take up wear and prevent a rattling motion between the bearing-surfaces.

Having fully described my invention, what I claim as new, and desire to secure by Letters Patent, is—

75

1. In vehicle-gears, the combination, with an elongated reach-plate having a transverse plate and a top circle-plate at its front end, the said reach-plate having a perforation therein, of the lower circle-plate having a centrally-located integral pin, and a bracket-plate secured to the reach and provided with lips which overlap the under surface of the lower circle-plate, substantially as set forth.

80

2. In vehicle gears, the combination, with a top circle-plate having an integral reach-plate projecting from it, and a lower circle-plate provided with a pin having swivel engagement with a perforation made in the integral reach-plate near the radial center of the top circle-plate, of a bracket-plate secured to the reach-plate by suitable means, and adapted to retain the lower and upper circle plates in place and take up wear, substantially as set forth.

90

3. In vehicle gears, the combination, with a spring, a head-block, a reach, a top circle-plate, and a reach-plate integral with this top circle-plate, of a lower circle-plate, a bracket-plate, a set-bolt secured in this bracket-plate, an axle, a wooden axle stock, clamping-plate bolts to hold the axle-stock, axle, and clamping-plate together, a depending pin formed on the clamping-plate, and a diagonal brace that engages this pin and is attached to the reach-plate and reach, substantially as set forth.

105

4. In vehicle-gears, the combination, with the reach-plate perforated to receive a cylindrical pin, and a lower circle-plate with its transverse axle-plate that is provided with a cylindrical pin, of a bracket-plate secured to the lower side of the reach-plate and having a lug which is adapted to loosely secure the lower circle-plate in position, substantially as set forth.

110

In testimony whereof I have signed this specification in the presence of two subscribing witnesses.
